UNITED STATES PATENT OFFICE.

STANLEY JOHN KUZIEL, OF HOLYOKE, MASSACHUSETTS.

COMBINED CURTAIN AND SHADE SUPPORT.

Application filed February 8, 1924. Serial No. 691,414.

To all whom it may concern:

Be it known that I, STANLEY JOHN KUZIEL, a citizen of the United States, and a resident of Holyoke, in the county of 5 Hampden and State of Massachusetts, have invented a new and Improved Combined Curtain and Shade Support, of which the following is a full, clear, and exact description.

10 This invention relates to improvements in combined curtain and shade supports, and has for one of its objects to provide a device of this character which is simple in construction and which may be readily and 15 quickly attached to a window frame in a secure manner without the use of screw fasteners or the like.

The above and other objects will appear more clearly from the following detailed 20 description, when taken in connection with the accompanying drawing, which illustrates preferred embodiments of the inventive idea.

In the drawing—

25 Figure 1 is a perspective view of one form of the invention showing its application to a window frame;

Figure 2 is a section on the line 2—2 of Figure 1;

30 Figure 3 is a section on the line 3—3 of Figure 1;

Figure 4 is a section on the line 4—4 of Figure 1;

35 Figure 5 is a section on the line 5—5 of Figure 1; and

Figure 6 is a perspective view of a slightly different form of the invention.

Referring more particularly to Figures 1 to 5 inclusive, the numeral 10 indicates the 40 base plate or body portion of the device which is provided with a lateral flange 11 at its top adapted to fit over a projecting portion 12 of the window frame to suspend the device therefrom, it being understood that 45 one of the devices is mounted at each end of the upper portion of the window frame. Associated with the base plate 10 is an adjustable slide 13 movable vertically between

guide lugs 14 formed on an extension 15 of said base plate and having at one end a finger piece 16 which may be gripped to facilitate the adjustment of said slide. The slide is provided with a longitudinal slot 17 therein through which extends a set 55 screw 18 carried by the extension 15 and having a wing nut 19 thereon for securing

the slide in various adjusted positions. A resilient supporting member 20 in the form of a single length of wire is bent intermediate its ends to provide the parallel portions 21 which extend between the slide 13 and extension 15 and the loop-shaped connecting portion 21^a of which engages an inwardly projecting lug 16^a at the upper end of the slide and secures the portion 21 of the member 20 to the said slide. The portions 21 extend longitudinally of the slide and at their lower ends are bent to provide the spring coils 22 from which the extremities of the wire are extended and bent to 70 provide pivotal connections 23 with a clamping plate 24 which may have a layer of felt or other suitable material 25 secured thereto and capable of engaging a portion of the window frame, as clearly shown in 75 Figures 1 and 2. By reason of the resiliency of the coils 22 a pressure is exerted upon the clamping plate which will cause the same to closely adhere to the window frame and materially aid in supporting the device in 80 position thereon.

By adjusting the slide 13, the strain in the coils 22 of the member 20 can be increased or decreased.

The base plate 10 is also provided with 85 guide lugs 26 and a strap 27 in which is slidably mounted a shade bracket 28 held in position by a suitable set screw 29, said bracket being utilized to support a shade roller, as indicated in dotted lines in Figures 1 and 4.

The base plate is also provided with straps 30 and 31 in which is slidably mounted a curtain support 32 in the form of a single length of wire engageable in both of 95 the straps, the strap 31 being yieldably held in position by a set screw 33 about which the spring 34 is coiled. The strap 30 and another strap 35 are utilized to carry another support 36 made of a single length 100 of wire adjustable in said straps and designed for the purpose of supporting curtain draperies.

The construction shown in Figure 6 is utilized for attachment to the vertical stile 105 37 of a window frame and consists of a base plate 38 having a flange 39 at one end engaging the outside edge of the stile and having supports 40 and 41 for carrying a shade and curtain. The plate is provided with guide lugs 42 in which is adjustably mounted a slide 43 similar in construction to the

slide 13 and between which and the base plate is interposed a supporting member 44 similar to the member 20 and including the coils 45 which are connected to the clamping plate 46 which, in this instance, engages the inner vertical edge of the stile 37.

What is claimed is:

1. A device of the character described including a base plate, a slide member adjustable thereon, a resilient supporting member interposed between said base plate and slide and held in position thereby, and a clamping plate carried by said supporting member and engageable with the window frame to hold said base plate in position thereon.
2. A device of the character described including a base plate, a slide member adjustable thereon, a resilient supporting member interposed between said base plate and slide and held in position thereby, a clamping plate carried by said supporting member

and engageable with the window frame to hold said base plate in position thereon, a shade support adjustably mounted on the base plate, and a plurality of curtain supports adjustably and independently mounted on said base plate.

3. A device of the character described including a base plate capable of engagement with a window frame, a slide member adjustable on said base plate, a supporting member formed of a single length of wire having its intermediate portion interposed between said base plate and slide member and held in position thereby, other portions of said supporting member being bent to provide coil springs, and a clamping member pivotally connected to the extremities of said wire and engageable with a portion of the window frame to clamp said base plate in position thereon.

STANLEY JOHN KUZIEL.
